ATTORNEY.

UNITED STATES PATENT OFFICE.

GEORGE H. PRATT, OF WHITE PLAINS, NEW YORK.

DESIGN FOR A TUMBLER-HOLDER.

41,296.

Specification for Design. Patented Apr. 11, 1911.

Application filed February 6, 1911. Serial No. 607,001. Term of patent 7 years.

To all whom it may concern:

Be it known that I, GEORGE H. PRATT, a citizen of the United States, residing at White Plains, in the county of Westchester and State of New York, have invented a new, original, and ornamental Design for a Tumbler-Holder, of which the following is a specification, reference being had to the accompanying drawing, forming part thereof.

The figure is a perspective view of a tumbler holder, showing my new design.

I claim:

The ornamental design for a tumbler holder, as shown.

GEORGE H. PRATT.

Witnesses:

FREDERICK WM. EGGERS,

CLARENCE J. COOK.
